(57) **CLAIM**

The ornamental design for a heel protector, substantially as shown and described.

DESCRIPTION

FIG. 1 is an isometric view of a heel protector according to one embodiment of the present invention shown in use on a shoe;

FIG. 2 is an isometric view of the heel protector of FIG. 1; FIG. 3 is a front elevation view of the heel protector of FIG. 1; FIG. 4 is a rear elevation view of the heel protector of FIG. 1; FIG. 5 is a left side elevation view of the heel protector of FIG. 1;

FIG. 6 is a right side elevation view of the heel protector of FIG. 1;

FIG. 7 is a top plan view of the heel protector of FIG. 1;

FIG. 8 is a bottom plan view of the heel protector of FIG. 1; FIG. 9 is an isometric view of a heel protector according to another embodiment of the present invention shown in use on a shoe;

FIG. 10 is an isometric view of the heel protector of FIG. 9; FIG. 11 is a front elevation view of the heel protector of FIG. 9;

FIG. 12 is a rear elevation view of the heel protector of FIG. 9;

FIG. 13 is a left side elevation view of the heel protector of FIG. 9;

FIG. 14 is a right side elevation view of the heel protector of FIG. 9;

FIG. 15 is a top plan view of the heel protector of FIG. 9; FIG. 16 is a bottom plan view of the heel protector of FIG. 9; FIG. 17 is an isometric view of a heel protector according to another embodiment of the present invention shown in use on a shoe;

FIG. 18 is an isometric view of the heel protector of FIG. 17; FIG. 19 is a front elevation view of the heel protector of FIG. 17;

FIG. 20 is a rear elevation view of the heel protector of FIG. 17;

FIG. 21 is a left side elevation view of the heel protector of FIG. 17;

FIG. 22 is a right side elevation view of the heel protector of FIG. 17;

FIG. 23 is a top plan view of the heel protector of FIG. 17; FIG. 24 is a bottom plan view of the heel protector of FIG. 17; FIG. 25 is an isometric view of a heel protector according to another embodiment of the present invention shown in use on a shoe;

FIG. 26 is an isometric view of the heel protector of FIG. 25; FIG. 27 is a front elevation view of the heel protector of FIG. 25;

FIG. 28 is a rear elevation view of the heel protector of FIG. 25;

FIG. 29 is a left side elevation view of the heel protector of FIG. 25;

FIG. 30 is a right side elevation view of the heel protector of FIG. 25;

FIG. 31 is a top plan view of the heel protector of FIG. 25; and, FIG. 32 is a bottom plan view of the heel protector of FIG. 25. The broken lines in the drawings represent unclaimed environmental subject matter and form no part of the claim.
